UNITED STATES PATENT OFFICE.

WILLIAM BLOOMBERG, OF NEW YORK, N. Y.

DESIGN FOR A SUSPENDER-END.

SPECIFICATION forming part of Design No. 27,584, dated August 31, 1897.

Application filed July 10, 1897. Serial No. 644,148. Term of patent 7 years.

To all whom it may concern:

Be it known that I, WILLIAM BLOOMBERG, a citizen of the United States, residing at New York city, in the county and State of New York, have invented and produced a new and original Design for a Suspender-End, of which the following is a description, reference being had to the accompanying drawing, forming a part thereof, in which is shown a front elevation of a suspender-end embodying the features of my design.

The suspender-end A includes the body portion 10, which is to enter the buckle-piece of the suspender, and the tabs 11, containing the buttonholes 12.

The feature of the design consists in carrying from each end portion of the body 10 a strap or tape 13, the straps or tapes being brought together at their lower ends and made to constitute a portion of a clip 14. 20

I claim—

The design for a suspender-end, substantially as shown and described.

WILLIAM BLOOMBERG.
